JOHN T. PHIPPS, OF LOS ANGELES, CALIFORNIA.

ROTARY WELL DRILL.

Application filed February 18, 1926. Serial No. 89,044.

This invention relates to rotary well drills and is particularly directed to drills of the character adapted for use in conjunction with the circulating fluid system of well 5 drilling.

In the usual rotary drilling system, the drill is attached to the lower end of a string of drill pipe which is rotated by a rotary table at the well surface and fed downward- 10 ly with the progress of the drill, and mud-laden fluid is pumped down the hollow drill pipe to be discharged through circulation passages in the drill, said mud laden fluid flushing the drill and transporting the drill- 15 ing detritus upwardly between the drill pipe and the wall of the well bore and to the surface where it flows into a settling sump and is available for recirculation. The mud-laden fluid further serves the very useful 20 purpose of mudding up the wall of the well bore and preventing caving in of the formation.

In many types of rotary drills, and particularly in the ordinary type of fish-tail bit, the circulation passages discharge the circulation fluid at points spaced a considerable distance from the cutting edges and the bottom of the well bore, and consequently when drilling in soft sticky formation 25 there is a great tendency for the drill to "mud-up", that is, the sticky mud is very liable to adhere to and pack solidly on that portion of the drill below the effective flushing action of the streams of fluid discharging 30 from the circulation passages of the drill, with the result that the drill is unable to make progress and may even become 35 "froze" in the well bore. This is due to the fact that even when the fluid is discharged 40 from the circulation passages of the drill under considerable pressure, into the body of fluid in the well bore, the flushing velocity of the fluid is dissipated within a few inches 45 of the outlet of said passages and said fluid does not reach the bottom of the well bore. As the outlets of said passages in many cases, especially in the ordinary fish-tail drill, are 50 as much as two feet from the lower cutting edges of the drill, it will be evident that the circulation reverses before reaching the bottom and consequently the bottom of the bore contains fluid not subjected to circulation or to flushing action. This dead fluid zone is

the main cause of the "mudding-up" of rotary drills. 55

In many instances this undesirable condition has been partially overcome by carrying the circulation passages the entire length of the drill body to discharge close to the bottom of the drill and while this in some 60 measure eliminates a portion of the trouble, the present invention has for an object to provide an improved arrangement of circulation passages in a rotary drill, by means of which "mudding-up" of the drill will be fur- 65 ther if not entirely eliminated.

A further object is to incorporate such improved arrangement of circulation passages in a drill of the fish-tail type.

Another object is to provide a fish-tail 70 drill of the above character in which is included a replaceable cutting blade.

Various other objects and advantages will be more fully apparent from the following description of the accompanying drawings 75 which form a part of this disclosure, and which illustrate a preferred form of embodiment of the invention.

Of the drawings:

Fig. 1 is a side elevation of my improved 80 drill.

Fig. 2 is a bottom plan view.

Fig. 3 is a vertical section of the drill body taken on line 3-3 of Fig. 2, the detachable blade and retaining pin having 85 been removed.

Fig. 4 is a vertical section on line 4-4 of Fig. 2.

Fig. 5 is an enlarged plan section on line 5-5 of Fig. 1. 90

Fig. 6 is a perspective view of the detachable blade.

Fig. 7 is a side elevation of an integral fish-tail bit having the improved circulation passage arrangement of the present invention. 95

Fig. 8 is an edge elevation of the bit shown in Fig. 7.

Fig. 9 is a vertical section on line 9-9 of Fig. 7. 100

Referring particularly to Figs. 1 to 6, 10 designates a one-piece drill body of considerable length and of general cylindrical contour, having diametrically disposed wing portions 11 which are of substantial width to 105 provide peripheral surfaces 12 of sufficient

area to effectively serve as means for guiding the drill in a manner to produce a substantially straight well bore and also as a means for keeping the mud-laden fluid stirred up while the drill is rotating.

The upper end of the drill body 10 is provided with the usual form of screw-threaded tapered pin 13 so that the drill may be attached in the usual manner to the lower 10 end of a string of drill pipe and the lower end of the body is suitably rounded so as to offer the least possible resistance to the flow of the circulation fluid.

The preferred type of detachable cutting 15 blade comprises a body portion 14 having its lower end dressed in the well known fish-tail manner, and a shank 15 extending upwardly therefrom, said shank being of less width than the body portion and having 20 rounded side edges, as clearly shown in Figs. 5 and 6. One side surface of said shank 15 is transversely grooved as at 16, said groove being of semi-circular contour and adapted in conjunction with a similar 25 groove in the drill body to receive a round retaining pin 17.

The lower end of the body 10 is slotted upwardly as at 18, said slot extending diametrically in the plane of the opposed 30 wings 11 and passing transversely entirely through the body proper and said wings. Continuing upwardly from said slot the body is recessed as at 19 to receive the shank portion 15 of the detachable blade, said recess being of less width than the body and contoured in a manner corresponding to the shape of said shank portion of the blade. (See Figs. 1 and 5.)

At 20 the body is transversely bored at an 40 elevation to coincide with the position of the groove 16 in the shank 15 of the blade when said blade is in place, the medial portion of the bore 20 intersecting the recess 19 to form the semi-circular groove 21 complementary to the groove 16, said grooves cooperating to complete the circular hole accommodating the retaining pin 17. As illustrated in Figs. 45 1 and 5, the bore 20 is shouldered at 22 and has a terminal end 23 of reduced diameter 50 and the opposite wing 11 has a bore 24 having a tapped end to receive a screw-threaded locking pin 25.

In assembling the blade 14 into the drill body, it is inserted upwardly in the slot 18 55 with its shank 15 disposed within the recess 19 and its groove 16 in registry with the groove 21 in the side wall of said recess and the bore 20. The retaining pin 17 is then inserted into the bore 20 until it engages the shoulder 22, after which the locking pin 25 is screwed into the bore 24 with its inner end extending across the bore 20 to lock the retaining pin 17 in place. When it is desired to remove the blade, and after the 60 locking pin 25 is first removed, the retaining

pin 17 may be driven out by a punch or other suitable instrument inserted into the reduced terminal end 23 of the bore 20.

Referring now more particularly to the circulation arrangement, it will be observed 70 that the body of the drill is provided with a central bore 26 extending downwardly from the upper surface of the tapered pin 13. To facilitate manufacturing this central bore intersects the recess 19 although from the 75 standpoint of function this is not essential. The upper end of the bore 26 communicates with the interior of the string of drill pipe through which the circulation fluid is pumped downwardly to the drill, and intersecting said bore 26 and slightly diverging downwardly are two circulation passages 27 discharging downwardly at the lower end of the body respectively on opposite sides of the cutting blade 14. It will be noted 80 that these circulation passages are disposed each to discharge its flushing jet in front of the adjacent cutting edge of the blade.

This arrangement provides downward circulation discharging from the lower end 90 of the drill closely adjacent the bottom of the well bore and eliminates any zone of non-circulating fluid which would tend to induce "mudding-up" of the drill.

To accelerate the return circulation and the elevation of the drilling detritus I provide additional circulation passages 28 discharging a portion of the circulation fluid upwardly along opposite sides of the drill body, these passages 28 communicating at 100 their lower ends with the central bore 26 through short transverse passages 29 formed by boring into one side of the drill body, the outer end of said bore being subsequently closed by a plug 30 welded or otherwise secured in place.

In Figs. 7 to 9, the circulation arrangement above described is shown as applied to an integral fish-tail bit, in which the medial portion 31 of the blade is enlarged 110 to cylindrical form and extends to within a short distance of the bottom or cutting edge of the blade. A central bore 26 extends downwardly from the upper surface of a tapered pin 13^a and communicates with a transverse passage 29^a formed by boring into one side of the body and subsequently closing the end of said bore by a plug 30^a. Circulation passages 27^a extend downwardly 115 from said passage 29^a and discharge upon opposite sides of the cutting blade, and return circulation passages 28^a extend upwardly from said passage 29^a and discharge upwardly along opposite sides of the body.

The improved arrangement of circulation 120 passages or parts herein described provides downwardly directed flushing jets discharging sufficiently close to the bottom of the well bore to insure quick elevation of all 125 of the drilling detritus, and provides means

for reversing a portion of the circulating fluid within the drill body and for directing flushing jets upwardly to accelerate the return circulation.

5 While the particular embodiment herein illustrated and described is well adapted to fulfill the objects primarily stated, it is to be understood that the scope of the invention is not limited thereto, for it is susceptible of embodiment in various other forms, all coming within the scope of the following claims.

I claim as my invention:

1. A rotary drill comprising a body having means at its upper end for attachment to a drill pipe and provided with cutters at its lower end, there being a bore extending downwardly and terminating in said body and positioned to receive circulation fluid 15 from said drill pipe, said body being provided with circulation passages for reversing the circulation within the body and discharging upwardly and exteriorly of the body and other circulation passages extending 20 to the lower end of the body and discharging a portion of said fluid towards the cutters.

2. A rotary drill comprising a body having means at its upper end for attachment to a drill pipe and provided with cutters at its lower end, there being a central bore extending downwardly and terminating in said body and adapted to receive circulation fluid from said drill pipe, said body being provided 30 with circulation passages communicating with said central bore and positioned to reverse the circulation within the body and discharge upwardly and exteriorly of the body and other circulation passages communicating with said central bore and extending 35 downwardly to the lower end of the body and discharging a portion of said fluid towards the cutters.

3. A rotary fish-tail drill comprising: a body having a transverse cutter blade extending below its lower end and provided with a screw-threaded tapered pin at its

upper end, said body having a bore extending downwardly from the upper surface of said pin and terminating within said body 50 and circulation passages communicating with said bore and extending downwardly to the lower end of the body and discharging on opposite sides of said cutter blade, and other circulation passages communicating with said bore and extending upwardly to reverse a portion of the circulation fluid within the body and discharging said fluid upwardly along the exterior of the body. 55

4. In a rotary fish-tail drill, the combination of: a body having means at its upper end for attachment to a drill pipe and provided at its lower end with a diametric slot extending upwardly into the body, said body being provided with a recess extending upwardly from the base of said slot; a detachable cutting blade positioned in said slot and extending below the body, said blade having a shank extending into said recess and provided with a transverse groove cut 70 into one of its side surfaces, the body being provided with a transverse bore registering with said groove; and a retaining pin extending through said bore and said groove, said body having a bore extending 75 downwardly and positioned to receive circulation fluid from said drill pipe, there being a circulation bore extending downwardly and terminating in said body and circulation passages in said body communicating with said circulation bore and extending 80 downwardly to the lower end of the body and discharging on opposite sides of said cutting blade, said body being further provided with other circulation passages communicating with said bore and extending upwardly to reverse a portion of the circulation fluid within the body and discharge 85 said fluid upwardly along the exterior of the body. 90

In testimony whereof, I have hereunto set my hand at Los Angeles, California, this 11th day of February, 1926.

JOHN T. PHIPPS.
